UNITED STATES PATENT OFFICE

HAROLD W. SHONNARD, OF MONTCLAIR, NEW JERSEY, ASSIGNOR TO ELEVATOR SUPPLIES COMPANY, INC., A CORPORATION OF NEW JERSEY

DOORCHECK

Application filed February 20, 1926. Serial No. 89,566.

The present invention relates to an improved form of door check whereby slamming of the door is prevented both in opening and closing the door. My improvement is particularly designed for use in connection with the type of sliding doors commonly used on elevator shafts, although it is to be understood that I do not limit myself to the application to doors of this or of any particular style or type.

Cylinder and piston door checks of the general type to which this invention belongs have been used in which the slamming of the door when closed was prevented by the checking of a body of liquid, preferably oil, which is forced through a narrow adjustable opening on the down stroke of the piston. My present invention has relation to a novel construction applicable to door checks of this kind whereby they may be made effective against slamming in both directions by a simple and inexpensive means involving no change in that part of the device which acts to check the door when closed.

The invention is illustrated in a preferred form in the accompanying two sheets of drawing which together exhibit a longitudinal section of a door check embodying my present improvement.

This drawing shows one well known form of door check as heretofore used for preventing the slamming of the door or gate when closed, to which has been added my improvement; whereby this form of apparatus is made effective in opening as well as in closing the door or gate.

In the well known door checks already in use, the closed cylinder 10 is provided with a head 11 which is pivotally attached to an appropriate fixed bracket shown in dotted lines at 12. Within an extension 13 to the head 11 there slides a piston 14 having a piston rod 15 which passes through a stuffing box 16 in the cap 17, and is attached to a movable part connected with the door or gate, as

for instance, the swinging lever indicated in dotted lines at 18.

There is fixed to the movable piston rod 15 a spider 19 having a flange 20, against which bears the spring 21 the pressure of which operates to close the door. Of course, where the door is not closed automatically this spring may be omitted. It is also to be understood that, if desired, door closing means other than a spring may be used, without departing from the invention.

In use the device shown is located with the head 11 lower than the cap 17, and the lower end accommodates a body of liquid, preferably oil, which acts as a retarding agent. When the door approaches its closed position, the oil below the piston 14 is forced through the passage 22 and adjustable needle valve 23, thus finding its way to the back of the piston 14, and through the passage 24 to the space within the outer cylinder 10.

In setting out to produce the same checking effect on the opening of the door, it is theoretically possible, of course, to simply provide the upper end of the cylinder extension 13 with an equipment similar to that just described at the lower end.

Such a construction, however, would be difficult and expensive to produce, as it would necessitate the provision of a stuffing box like that shown at 16 placed in exact alignment with the stuffing box and would exclude all possibility of eccentric movement of the piston rod 15.

My invention is designed to obviate this difficulty and expense, by providing an effective checking means on the up stroke of the piston which is inexpensive in construction, which can be readily applied to the forms of checks already in use, and which will do away with an extra stuffing box and permit eccentric movements of the piston rod 15 within the scope to be reasonably expected in practice.

For this purpose the cylindrical extension 19

13 of the head 11 is furnished with a head 25 having a central opening 26 the diameter of which is sufficiently greater than that of the piston rod 15 to prevent all danger of binding when the piston 14 moves back and forth. The resulting clearance around the rod 15 is clearly shown in the drawing.

Inside of the head 25, a movable sleeve 27, made of fibre or other appropriate material, is carried upon the piston rod 15. This sleeve makes a sliding fit with the piston rod, so that it moves back and forth with it.

In order to limit the extent to which this sleeve 27 may be moved away from the head 25, headed screws 28 are used which pass through openings in the sleeve 27 and are screwed into the head 25. The openings in the sleeve through which these screws pass are made larger than the screws, so that a limited lateral motion of the piston rod and sleeve may be permitted for the purposes above described.

Now when the door is opened and the piston 14 moves upward, the weight of the sleeve 27 prevents its upward movement so long as there is a free passage of the oil through the opening 24, and consequently the movement of the piston 14 is quite free while the opening 24 is clear. When the piston 14 passes this opening, however, the resultant pressure forces the sleeve 27 against the inner face of the head 25, thus closing the opening 26 around the piston rod; and further movement of the piston can only be accomplished at the reduced speed permitted by the resistance of the oil as it is forced through the opening 29, the passage 30 and the adjustable needle valve 31 into the space within the outer cylinder 10. This effectively checks the opening of the door toward the end of the opening movement, and prevents slamming.

What I claim is—

1. In a door check, a cylinder having a restricted oil exit at one end, a piston in said cylinder, a piston rod operatively connected to said piston, a closing head at said end of the cylinder having a central opening somewhat larger than the piston rod, and means adapted to be operated by pressure of the oil in one direction to close said space around the piston rod.

2. Apparatus as in claim 1 wherein the means for closing the space around the piston rod is a sleeve on the piston rod making a suitable fit therewith.

3. Apparatus as in claim 1 wherein the means for closing the space around the piston rod is a sleeve on the piston rod making a suitable fit therewith, said sleeve having headed retaining means passing through it and fixed to the cylinder head, whereby the distance the sleeve can be moved from the cylinder head is limited.

4. In a door check, a dashpot cylinder, a piston therein, a closing head at one end of

said cylinder having a passage adapted to permit a limited flow of oil therethrough during movement of the piston in the door closing direction, and means adapted to be operated by oil pressure within the cylinder to close said passage during a portion of the movement of the piston in the door opening direction.

In testimony whereof I have hereto affixed by signature on this 18th day of February 1926.

HAROLD W. SHONNARD.
